UNITED STATES PATENT OFFICE.

JOHN PHILLIPS, OF ST. LOUIS, MISSOURI; MARY M. PHILLIPS ADMINISTRATRIX OF SAID JOHN PHILLIPS, DECEASED.

CRIMPING-MACHINE.

SPECIFICATION forming part of Letters Patent No. 374,082, dated November 29, 1887.

Application filed May 29, 1885. Serial No. 167,008. (No model.)

To all whom it may concern:

Be it known that I, JOHN PHILLIPS, of St. Louis, in the State of Missouri, a citizen of the United States, have invented a new and useful Improvement in Boot and Shoe Crimping Machines, of which the following is a full, clear, and exact description, reference being had to the accompanying drawings, forming a part of this specification, in explaining its nature.

10 The principal object of the invention is to provide a crimping-machine with crimping-jaws which move both vertically and laterally, so that its action upon the upper as it is presented to them shall be as nearly at right angles to the working-edge of the crimping frame or support as desirable.

Another object of the invention is to provide the boot or shoe upper, while it is passing through the crimping-jaws, with a considerable extent of travel, so as to stretch the leather in the right direction, and get as much "corner," as it is termed, as possible without injury to the stock.

It also relates to various features of construction, all of which will be hereinafter more fully described.

Referring to the drawings, Figure 1 represents a front elevation of a machine containing my invention. Fig. 2 is a side elevation thereof. Fig. 3 is a plan view thereof. Fig. 4 represents a section upon the line $x-x$ of Fig. 1, and a side elevation of the portion of the frame to the left thereof. Fig. 5 is a section upon the line $y-y$ of Fig. 1. Fig. 6 is a section upon the line $z-z$ of Fig. 1. Figs. 7 and 8 are detail views.

A A' are the side frames of the machine.

A² is an upper cross-girth, and A³ a lower cross-girth, connecting the two frames.

40 B is a cross-head, carrying or supporting the crimping block or form b, which is removable therefrom.

The cross-head is adapted to be vertically reciprocated, and I will hereinafter describe one means of so moving it. This vertical movement of the cross-head moves downward the crimping form or block between the crimping-jaws C C', between which is arranged a narrow space, into which the crimping form or block with the upper thereon is

forced. Each of these jaws has, in substance, three parts—first, the central section, c, which is in the form of a long wedge; second, the side pieces, c' c', and, third, the end part or piece, c², secured to the upper end of the wedge. 55

The side pieces, c' c', are arranged in relation to the wedge substantially as shown in Fig. 1—that is, their inner edges, c³, bear upon the inclined surfaces c⁴ of the wedge c. In other words, the wedge is between these 60 two parts c' c', and so disposed in relation to them that its movement shall cause them to be separated or brought together, according as the wedge moves, and without breaking joints.

The working-faces of each jaw, comprising 65 the face of the wedge c and the faces or side surfaces of the parts c' c', are upon the same line, or substantially the same line.

In the drawings I have represented the parts c' c' of the jaws as supported by the cross-piece 70 D, which has the downward and outwardly-extending supports d', in which are formed dovetail ways or recesses for the support of the parts c' c', which have dovetail projections or tongues entering said dovetail recesses. This 75 construction is shown in section in Fig. 6. I have also shown the wedges vertically movable in relation to the jaws C C', so that their upward movement shall cause the parts c' c' to be moved laterally, or away from each other; 80 and upon the downward movement of the wedges these parts are returned or moved toward each other by the springs e e', the diverging movement of the parts c' c' upon the upward movement of the wedges causing the 85 springs to be compressed. In lieu of this construction, the back sides of the wedges may be provided with grooves parallel with their inclined surfaces for the reception of pins or rolls secured or fastened to the parts c' c'. The 90 grooves will then act as guides in opening or moving apart and closing or drawing together the parts c' c', according as the wedge is moved up or down; and I would here remark that instead of moving the wedge vertically it may 95 be stationary and the parts c' c' made movable vertically in relation to it.

It is quite essential that the two jaws have a horizontally-yielding movement sufficient to enable the crimping-form to present uppers of 100

varying thickness to the jaws without injury, and I have shown each of the supports D and sections $c' c'$ of the jaws as arranged to yield horizontally from each other. This construction is shown in Fig. 4, where FF' represent the ends of the support D, and f the holes or apertures in the frame which receives and holds the ends. f' are bearing-plates moved by the springs f² against the end portions of these 10 pieces and act as a spindle to move them toward each other with a proper degree of pressure, but not sufficient, however, to prevent the parts D from being moved away from each other or separated upon the presentation to the jaws of 15 upper-leather of increased thickness. It is of course essential that the guides also have the same yielding movement; and this is provided in substantially the same way by means of the spring-held bearing-plates G G', (see 20 Fig. 5,) the bearing resting against the outer surfaces of the wedges c c, (see Fig. 5,) g representing the supports for the springs g², which press against the bearing-plates. I may, however, use any other equivalent yielding supports for the jaws.

The wedges c are supported by the cross-head H, and it and the cross-head B are movable to and from each other by the following means: The cross-head B has secured to each 30 end the rack b', which extends downward to engage with the teeth of the pinions b², operated by the gears b³ upon the shaft b⁴. The cross-head H has attached at each end the racks h, the teeth of which are adapted to engage with 35 the teeth of the gears b³. It is necessary, however, that the cross-head B commence to move before the cross-head H and the wedges, in order that the upper may be well within or between the two jaws before the side pieces or 40 sections, c' c', of the jaws are caused to exert their special action; and in order that this may be accomplished, I have arranged each of the racks h to be held away from the gears b³ until the pinions b² have moved the cross-head 45 B sufficiently to bring the crimping-form b between the jaws C C'. When this has been done, the rolls h', carried by the arms h², extending from the racks b', come in contact with the inclines h³ upon the upper outer surfaces 50 of the racks h, and, riding thereon, draw the racks h inward or toward the racks b' and cause the teeth of the racks h to engage the teeth of the gear b³. This starts the operation of the wedges, and they are moved upward 55 while the crimping-form is yet moving downward, and the sections c' c' of the jaws are thus caused to move outward and thereby exert upon the portions of the upper against which they are brought in contact a wiping and feeding action from the edge of the crimping-form inward. This movement continues until the entire upper has been subjected to the fitting or crimping manipulations, and the travel of the cross-head and jaws in relation 60 to each other is such that the entire area of the upper is subjected to the crimping and stretching action of the jaws.

The relative movements of the upper cross-head, B, and lower cross-head, H, in relation to each other may be varied, as desired. Upon 70 the end of the respective movements of the cross-heads the machine comes to rest, and is then reversed, and upon the rolls h' leaving the inclines h³ the racks h are automatically drawn from their operating-gears b³ by means 75 of the springs k and lug k', which fits the dove tail or other recess in the racks, which allows or permits the movement of the racks in relation to it. These lugs k' are moved outward by the springs k.

I prefer that the surfaces of the jaws be provided with corrugations extending from the central line of the wedge-sections downward; but as this feature is common to other crimping-machines, I make no claim to it.

I would state that in lieu of making the wedges c movable they may be stationary, and the supports D and sections c' c' of the jaws made movable, and in the same time and in the same direction with the crimping block or frame. This construction is advisable when it is desirable to have a slow and long wiping and feeding action of the jaws C C'. The frame and the jaws may be moved downward by contact with the cross-head A therewith, 95 or by independent mechanism.

It is not necessary that each set of jaws C C' and each of the wedges c have lateral movements in relation to each other, as for certain kinds of work it will answer if only one set be provided with this adjustment.

Having thus fully described my invention, I claim and desire to secure by Letters Patent of the United States—

1. In a crimping-machine, the combination 105 of the crimping form or frame with the crimping-jaws having the laterally-movable sections c' c', all substantially as and for the purposes described.

2. In a crimping-machine, the jaws C C', 110 having the movable sections c' c' and the operating-wedges c, all substantially as and for the purposes described.

3. The combination, with the cross-head D, having the supports d', of the jaws having the 115 laterally-movable sections c', sliding in said supports, the wedges c, and the springs e, substantially as set forth.

4. In a crimping-machine, the combination 120 of the vertically-movable frame or form b, jaws having sections c' c', and the operating-wedges c, adapted to have movements in relation to each other, as specified, all substantially as and for the purposes described.

5. The combination of the crimping form 125 or frame b, the jaws C C', having the movable parts c' c', and the wedges c, adapted to be brought into operation after the frame or form b has moved between the jaws, all substantially as and for the purposes described.

JOHN PHILLIPS.
